[57] **CLAIM**

The ornamental design for a disposable lighter with integrated clip, as shown and described.

DESCRIPTION

FIG. 1 is a perspective view of a disposable lighter with integrated clip showing my new design;

FIG. 2 is a front elevational view thereof.

FIG. 3 is a rear elevational view thereof.

FIG. 4 is a right side elevational view thereof;

FIG. 5 is a left side elevational view thereof;

FIG. 6 is a top plan view thereof;

FIG. 7 is a bottom view thereof;

FIG. 8 is a second embodiment of the design shown in FIG. 1.

FIG. 9 is a front elevational view thereof.

FIG. 10 is a side elevational view thereof.

FIG. 1

FIG. 2

FIG. 3

FIG. 4

FIG. 5

FIG. 6

FIG. 7

FIG. 9

FIG. 10

FIG. 8
